UNITED STATES PATENT OFFICE.

GEORGE G. FLOYD, OF RIVERSIDE, ILLINOIS.

GOLF BALL.

Application filed February 11, 1925. Serial No. 8,355.

The present invention pertains to novel features of construction in balls in general, but the invention concerns more specifically, but not necessarily restrictedly, improvements in golf and similar balls, requiring a predetermined weight, size and degree of resiliency or elasticity.

One object or aim of the invention is the provision or production of a golf ball which will have all of the desired or required physical characteristics of the present balls used in the game of golf but which can be made materially less expensively than the balls now in common use.

To this end I do away with the comparatively costly winding of a rubber band upon itself under tension to form the core of the ball and as a substitute I employ relatively easily molded sections of resilient inexpensive material, such as compressed ground cork or equivalent material but to give the new ball the required weight I employ a core or center piece which is comparatively heavy, so that the ball as a whole will be of the needed diameter, and will possess the necessary weight and the proper degree of springiness or tendency to rebound.

Such a center piece or core can be conveniently made of a suitable metallic alloy, the weight of which can be readily governed or controlled through the proportions of the ingredients entering into such alloy.

To enable those skilled in this art to fully understand the advantages of the invention both from structural and functional standpoints, in the accompanying drawing forming a part of this specification I have illustrated a preferred and desirable embodiment of the invention, the single view representing a central section through the new and improved golf ball.

Referring to this drawing, it will be perceived that the ball incorporating this invention in its present desirable embodiment includes a spherical center piece or core 11 which is made of metal or preferably an alloy of aluminum and copper in such proportions or ratio that the ball as a whole will have the correct or proper weight, standard golf balls at the present time weighing approximately 1.62 ounces.

Inasmuch as the aluminum is a comparatively light metal and the copper a relatively heavy metal and since they are susceptible of forming an alloy throughout a

large range of proportions no difficulty is encountered in making this core or center of the required weight.

Such core, which may be of any appropriate or suitable size, is encased or enclosed in a resilient or elastic cover 12, composed of two, hollow, semi-spherical sections adhered or cemented together along their meeting edges or margins and to the core, or either such adhesion may be omitted if satisfactory results can be otherwise accomplished.

One applicable or fitting material, because of its comparative cheapness and adaptability to molding conditions to form the sections, is hard pressed or condensed ground cork which possesses the necessary elastic qualities.

Obviously, the use of such a core and the molded sections of its resilient cover eliminates the necessity for a wound rubber core or in fact any rubber at all, and hence substantially reduces the cost of manufacture and sale price of the article.

The core and its elastic cover are supplied with an outer covering or casing 13 of customary form and it may have a plurality of external depressions or recesses which are usual on balls of this type.

The diameter of the spherical core and the thickness of the resilient layer or stratum are such that the complete ball will have the required size, which at the present time is approximately 1.62 inches in diameter.

All of the parts of the ball are so made that it, as a whole, will possess the usual weight, size and elastic properties, whereby it can be readily used as an efficient substitute for the more expensive ball now in common use.

The invention is not limited and restricted to the precise and exact details of structure presented because these may be modified within comparatively wide limits without departure from the heart and essence of the invention and without the sacrifice of any of its material benefits and advantages.

For example, the core, if desired, may be made of a single metal, instead of an alloy, or it may be made of any other suitable material of the proper weight. Any other appropriate material may be employed instead of the compressed ground cork provided it can be molded into sections and these united

over or enclosing the inner core, and the number of sections of such covering is more or less immaterial.

I claim:

- 5 1. A golf-ball having a spherical metal alloy core composed of aluminum and copper and a hollow spherical sectional resilient cover directly encasing and centering said core.
- 10 2. A golf ball having a spherical core composed of an alloy of aluminum and cop-

per and a cover for said core comprising united sections of compressed ground cork.

3. A golf ball having a spherical core composed of an alloy of aluminum and copper, a cover for said core comprising two hollow semi-spherical sections of compressed ground cork cemented together and an outer covering for the ball.

In witness whereof I have hereunto set 20
my hand and seal.

GEORGE G. FLOYD. [l. s.]
